(57) **CLAIM**

The ornamental design for a coaxial cable connector with colored band, as shown and described.

DESCRIPTION

FIG. 1 is a perspective view of a coaxial cable connector with colored band showing my new design;

FIG. 2 is a front elevation view thereof;

FIG. 3 is an end view thereof; and,

FIG. 4 is an opposite end view thereof.

The stippled portion shown in FIGS. 1 and 2 represents different selected colors.

The broken line showing of the environment is for illustrative purposes only and forms no part of the claimed design.
